(57) **CLAIM**

The ornamental design for a surveillance camera, as shown and described.

DESCRIPTION

FIG. 1 is a perspective view of a surveillance camera, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged detail view of the indicated portion 9 in FIG. 1 thereof;

FIG. 10 is an enlarged detail view of the indicated portion 10 in FIG. 1 thereof; and,

FIG. 11 is an enlarged detail view of the indicated portion 11 in FIG. 2 thereof.

The broken lines shown in the drawings illustrate portions of the surveillance camera that form no part of the claimed design.

The dot-dash broken lines represent the designation of enlargement views and form no part of the claim.
